(57) **CLAIM**

The ornamental design for a band holster as shown and described.

DESCRIPTION

FIG. 1 is a perspective view of a band holster showing my new design according to a first embodiment;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view of the band holster in the first use state;

FIG. 9 is a perspective view of the band holster in the second use state;

FIG. 10 is another perspective view of the band holster in the second use state;

FIG. 11 is a perspective view of the band holster in the third use state;

FIG. 12 is an enlarged perspective view of detail “12” identified in FIG. 4;

FIG. 13 is an enlarged perspective view of detail “13” identified in FIG. 10;

FIG. 14 is a perspective view of a band holster according to a second embodiment;

FIG. 15 is a front elevation view thereof;

FIG. 16 is a rear elevation view thereof;

FIG. 17 is a left-side elevation view thereof;

FIG. 18 is a right-side elevation view thereof;

FIG. 19 is a top plan view thereof;

FIG. 20 is a bottom plan view thereof;

(Continued)

FIG. 21 is a perspective view of the band holster in the first use state;
FIG. 22 is a perspective view of the band holster in the second use state;
FIG. 23 is another perspective view of the band holster in the second use state;
FIG. 24 is an enlarged perspective view of detail “24” identified in FIG. 17;
FIG. 25 is an enlarged perspective view of detail “25” identified in FIG. 23;
FIG. 26 is a perspective view of a band holster according to a third embodiment;
FIG. 27 is a front elevation view thereof;
FIG. 28 is a rear elevation view thereof;
FIG. 29 is a left-side elevation view thereof;
FIG. 30 is a right-side elevation view thereof;
FIG. 31 is a top plan view thereof;
FIG. 32 is a bottom plan view thereof;
FIG. 33 is a perspective view of the band holster in the first use state;
FIG. 34 is a perspective view of the band holster in the second use state; and,
FIG. 35 is an enlarged perspective view of detail “35” identified in FIG. 29.
The broken lines shown on the front of the band holster are portions of the design which form no part of the claim. The

additional broken lines around the holster are environment and form no part of the claim. The dash dot broken lines indicate the boundary of the enlarged portions and form no part of the claimed design.
